(57) **CLAIM**

We claim the ornamental design for a self-powered power sensor PCB and bobbin mount thereof, as shown and described.

DESCRIPTION

FIG. 1 is a right side isometric top view of one embodiment of a self-powered sensor assembly, comprising a print circuit board (PCB), an antenna, a core, a winding and a bobbin mount, showing our new design.

FIG. 2 is a right side isometric bottom view thereof.

FIG. 3 is a rear side isometric top view thereof.

FIG. 4 is a rear side elevation view thereof.

FIG. 5 is a front side elevation view thereof.

FIG. 6 is a right side elevation view thereof.

FIG. 7 is a left side elevation view thereof.

FIG. 8 is a bottom side elevation view thereof.

FIG. 9 is a top side elevation view thereof.

FIG. 10 is a right side isometric top view of a bobbin mount respective of the embodiment of FIGS. 1 through 9.

FIG. 11 is a right side isometric bottom view thereof.

FIG. 12 is a bottom side elevation view thereof.

FIG. 13 is a top side elevation view thereof.

FIG. 14 is a right side elevation view thereof.

FIG. 15 is a left side elevation view thereof.

FIG. 16 is a rear side elevation view thereof.

FIG. 17 is a front side elevation view thereof.

FIG. 18 is a front side isometric top view of a part of the bobbin mount respective of the embodiment of FIGS. 10 through 17.

FIG. 19 is a front side isometric bottom view thereof.

FIG. 20 is a left side elevation view thereof.

FIG. 21 is a right side elevation view thereof.

FIG. 22 is a rear side elevation view thereof.

FIG. 23 is a front side elevation view thereof.

FIG. 24 is a bottom side elevation view thereof; and,

FIG. 25 is a top side elevation view thereof.
